UNITED STATES PATENT OFFICE.

HARRIE A. BALLARD, OF BOSTON, MASSACHUSETTS, ASSIGNOR TO UNITED SHOE MACHINERY CORPORATION, OF PATERSON, NEW JERSEY, A CORPORATION OF NEW JERSEY.

UPPER CREEASING.

Application filed August 9, 1923. Serial No. 656,471.

This invention relates to upper creasing and more particularly to the forming of an upstanding crease longitudinally of the toe of a shoe.

In certain classes of shoes, especially those wherein a one-piece tip is used, it is desired to provide an upstanding crease extending longitudinally of the toe of the shoe as a decoration. This crease is known as a "trouser crease", and it may extend as far forward as the welt crease of the shoe and as far rearward as the very top of the tongue. According to the dictates of fashion and the desires of the manufacturer, the length of the crease will be varied between these limits. If such a crease is made in the upper before it is made up into a shoe, then it is likely to become distorted and perhaps eliminated or entirely smoothed out in the lasting operation. Accordingly, it is desirable to provide some way of creasing the upper after it has been incorporated in a finished shoe. In endeavoring to secure an upstanding crease of this character, various arrangements have been suggested which have been unsatisfactory for the reason that they have always involved a rubbing action tending to burnish or glaze the surface of the upper adjacent the crease, thereby detracting from the desired appearance.

To avoid the disadvantages resulting from the arrangements heretofore proposed, one object of the invention is to provide an improved method of producing a crease in the upper of a shoe whereby said crease may be rendered permanent and any glazing or burnishing of the adjacent parts of the upper avoided.

According to this novel method a section of the upper along the line of the desired crease is pinched together, and, according to the preferred procedure, a portion of the upper is first raised by pressure from within the shoe as by means of a supporting rib above the level of the remainder of the upper, is then pressed closely against the sides of the rib, and is then separated from the rib and pinched still more closely together.

Another object of the invention is to provide an improved machine for forming a crease in the upper of a finished shoe, such that the crease will stay permanently raised above the adjacent surface.

With this object in view, an important

feature of the invention comprises an arrangement in which a supporting tree is provided with a thin rib or blade, whose longitudinal curvature corresponds to the curvature of the portion of the shoe which is to be creased, and a co-operating presser having a complementary curvature and adapted to press the upper over the blade and then against its sides. Preferably the presser member will be grooved to receive a part of the blade.

Another important feature of the invention relates to the arrangement of an improved creasing tool whereby a rubbing action between it and the outer surface of the upper is avoided. In the construction illustrated in the drawings and herein described, this result is secured by dividing the grooved creasing tool or presser member longitudinally through the center of the groove and providing means for separating the parts of the grooved tool prior to the time when it is pressed against the shoe, or the leather of the shoe is forced up into the groove of the tool. Means are also provided for bringing together the co-operating parts of the presser members to pinch a strip of the leather into an upstanding crease which will be permanent.

For a more complete understanding of the novel method and one form of apparatus by means of which it may be carried out, reference is had to the following specification taken in connection with the accompanying drawings in which

Fig. 1 is a side elevation of an upper creasing machine embodying the invention;

Fig. 2 is a top plan view of my novel presser member;

Fig. 3 is a side elevation of this presser member showing its relation to the ribbed work supporting tree;

Fig. 4 is a vertical section on the line 4—4 of Fig. 3;

Fig. 5 is a vertical section on the line 5—5 of Fig. 3;

Fig. 6 is a perspective view of a modified form of presser member;

Fig. 7 is a vertical section on the line 7—7 of Fig. 6;

Fig. 8 is an enlarged section showing the parts of the presser member gripping a piece of work against the upstanding rib or blade on the supporting tree;

Fig. 9 is a similar view showing the parts of the presser member pinching a strip of the upper into an upstanding crease; and

Fig. 10 shows one type of shoe in which a "trouser crease" has been formed.

A supporting frame 10 is provided with an overhanging arm 12, whose outer end 14 constitutes a vertical bearing for a sliding plunger 16 which is provided with a roller 18 at its upper end and which supports a presser member 20 at its lower end.

A work supporting tree 22 is detachably secured to the overhanging arm 12, and this tree is provided with a longitudinal rib or blade 24 having substantially parallel sides. The tree is preferably made with a triangular cross section, as shown in Fig. 4, to reduce its height while securing the necessary strength. Preferably the rib is formed by means of a separate blade inserted in a slot in the tree 22. This blade is slightly tapered along its top edge, as shown in Fig. 8, so that it may be separated easily from the leather and is formed with a rounded edge in order that it may not cut the leather.

Vertical movement of the plunger 16 to cause the presser member 20 to approach and recede from the work may be secured by means of any suitable apparatus such as that illustrated in Patent No. 1,002,393, issued September 5, 1911, upon the application of John S. Hansen. Briefly this comprises a three-arm actuating lever 29 pivoted at 30 in the frame of the machine and having its lower arm 32 provided with a depending bar 34 to which is adjustably secured a foot treadle 36. To the upper arm 38 of said lever there is pivotally attached a horizontal member 40 supported upon links 42 and provided with an extension 44 having a rounded end adapted to co-operate with the roller 18 to depress the plunger. Springs 46 are arranged to retract the actuating member 40, and by reason of the connection of this member with the upstanding arm 38, they will rotate said lever in a counter-clockwise direction, as viewed in Fig. 1. The third arm 50 of said lever projects forwardly and co-operates with a projection 52 extending inwardly from the plunger 16 and overlying the end of the arm 50.

Any suitable means may be provided for heating the presser member, and such means is indicated as comprising a metal piece 54 detachably secured at 56 to the bearing 14 and provided with a vertical face 58 resting against the face of the plunger 16. Electric cartridge heating units 60 may be utilized to supply heat to this member.

The presser member preferably comprises a bearing member 62 having a vertical flange 64 (Fig. 5) designed to be received in a slot in the plunger 16 and secured thereto by a set screw 66. The grippers 70 and 72 of the presser member are provided with ears

74 and 76 by means of which they are pivotally mounted upon a longitudinal pivot 78 traversing said bearing member 62. Recesses or notches are cut in the co-operating meeting edges of the lower side of said grippers to form a groove 80 running throughout the length of the lower edge of said presser member to receive and crease the fold of an upper. These recessed grippers are designed to depress a portion of the upper over the rib 24 and grip it thereagainst as indicated in Fig. 8. It should be noted that the longitudinal curvature of the rib 24 is substantially the same as the curvature of the rabbeted edges of the presser member, and that the extent of the presser member will vary in accordance with the type of shoe to be handled and the distance along the toe of the shoe over which it is intended to form a crease.

In order forcibly to urge the grippers together, studs 82 and 84 are mounted in corresponding apertures in said grippers and are provided with springs 86 bearing at one end against the nuts 88 on said studs and at the other end against the side of the gripper. If desired, set screws 90 may be used for maintaining the position of the heads of said studs.

When the presser member is being lowered to push the major portion of the upper below the top of the upstanding rib 24, it is desirable to separate the grippers in order to avoid any rubbing action and consequent burring of the leather, and for this purpose there is provided a headed stud or button 92, (Fig. 5) the shank of which passes through the gripper 70 and is arranged with its head bearing against the gripper 72. A hand lever 94 is pivotally mounted in lugs 96 formed on the exterior of the gripper 70 and is arranged with a lateral portion 98 (Fig. 2) bearing against the end of the shank of the button 92 and another lateral portion 100 bearing against the face of the gripper 70. The deflection of said lever 94 toward the front of the machine will cause a separation of the grippers.

For some purposes it may be found satisfactory to construct the device in the manner illustrated in Figs. 6 and 7 in which one gripper 172 of the presser member is formed integrally with the supporting flange 164 while the other gripper 170 is supported by means of the headed studs 182 and 184. Springs 186 and a lever 194 perform their functions in a similar manner as in the preferred form, and the meeting edges of the grippers are grooved at 180 just as are the meeting edges of the grippers of the preferred embodiment.

When the type of shoe being creased is a blucher such as is illustrated at 110 in Fig. 10, it may be desired to form a crease from the extreme end of the toe through the vamp 130

and whole length of the tongue. In such a case the shoe will be mounted upon the supporting tree 22 in the position indicated in Fig. 1, and the operator will depress the treadle to cause a rotation of the three-way lever 29 and consequent depression of the forwardly extending member 50. This will allow the plunger 16 carrying the presser member 20 to fall of its own weight and the operator will at the same time deflect the handle of the lever 94 toward the front so as to open by a substantial amount the groove 80 between the grippers 70 and 72. As the operator continues to depress the treadle to cause a rotation of the actuating lever 29, the extension 44 will come in contact with the roller 18 on the plunger 16, as indicated in dotted lines in Fig. 1, and forcibly depress the separated grippers against the work at each side of the rib 24 of the supporting tree. This will raise a strip of the work into the enlarged groove 80, and when the operator then releases the handle of the lever 94, the springs 86 will cause the grippers 70 and 72 to press the work tightly against the side edges of the rib or blade 24 which extends lengthwise of and is shaped complementarily to the groove 80 in said presser member. After a short interval, he will partially release the treadle of the machine and allow the springs 46 to retract the extension 44 and slightly to raise the plunger through the co-action of the parts 50 and 52. Partially owing to the fact that the presser member 20 is heated, the tendency is for the work to be separated from the rib 24 and to remain in the groove 80. As soon as this separation occurs, the springs 86 will be able to bring the grippers 70 and 72 still more closely together and thereby to pinch together the raised strip of the upper and permanently to set the upstanding crease 112 in the shoe. After the work has remained within the groove of the presser members for the desired interval, the operator will again deflect the handle of the lever 94 and separate the grippers sufficiently to allow the work to be removed from the machine.

It should be noted that in this method of operation there is no rubbing of heated presser members against the leather of the shoe, and consequently there is no burnishing or streaking of the work. It will be obvious that the shape of the longitudinal curvature of the presser member and that of the rib 24 may be varied to suit the particular style of shoe to be treated. Minor changes may be made in the manner of carrying out the method or of constructing a machine without departing from the spirit of the invention.

Having thus described my invention, what I claim as new and desire to secure by Letters Patent of the United States is:—

1. The method of producing a crease in

the toe of a finished shoe which consists in raising a portion of the upper along the line of the desired crease by pressure from within in the shoe and pinching together the raised portion so that an upstanding ridge or 70 crease will be formed.

2. The method of producing a crease in the upper of a finished shoe which consists in raising a portion of the upper above the level of the remainder of the upper, and applying heated members to exert lateral pressure against the sides of the raised portion to form an upstanding crease in the leather. 75

3. The method of producing a crease in the upper of a shoe which consists in supporting the upper upon a rib, pressing the upper closely against the sides of the rib, separating the upper from the rib, and pinching together the portion of the upper against which pressure has been exerted. 80 85

4. In a machine for forming an upstanding crease along the toe of a finished shoe, a supporting tree adapted for insertion within the shoe, said tree being provided with a thin rib or blade whose longitudinal curvature corresponds to the curvature of the portion of the shoe which is to be creased, said rib having substantially parallel sides and being arranged lengthwise of the shoe, and opposed means disposed outside the shoe 90 95 for pressing the upper over said blade and then against its sides, said means having a curvature which is complementary to the curvature of the blade.

5. In an upper creasing machine, a supporting tree provided with a narrow rib, said tree being adapted for insertion in a finished shoe, a grooved presser member arranged for cooperation with said ribbed tree, means to enlarge the groove of said presser member, and means to bring the presser member into co-operative relation with the tree. 100 105

6. In a machine for forming a crease along the toe of a finished shoe, relatively separable grippers disposed outside the shoe and means arranged for insertion within the shoe constructed and arranged to present a portion of the upper of the shoe in the space between said grippers. 110 115

7. In a machine for forming a crease in the toe of a finished shoe, a ribbed supporting member, and divided presser means disposed outside a shoe and having a pivoted jaw, said presser means being constructed and arranged to force a portion of the upper of the shoe over the rib of the support. 120

8. In an upper creasing machine, a divided presser member the parts of which are notched to provide co-operating recesses of a limited depth along their meeting edges arranged to receive and crease a fold of an upper. 125

9. In an upper creasing machine, a divided presser member having two parts the 130

- adjacent corners of which are each cut away to provide co-operating recesses of a limited depth along their meeting edges arranged to receive and crease a fold of an upper, and 5 means for urging the sections of said presser member together.
10. In an upper creasing machine, a divided presser member having two parts which are provided with co-operating rabbets of a limited depth along their meeting edges arranged to receive and crease a fold of an upper, and means for moving the sections of said presser member apart. 10
11. In an upper creasing machine, a divided presser member having two parts the adjacent faces of which are rabbeted to provide co-operating recesses of a limited depth along their meeting edges arranged to receive and crease a fold of an upper, means 15 for urging the sections of said presser member together, and means for moving said sections apart. 20
12. In an upper creasing machine, a divided presser member the parts of which are provided with co-operating recesses of a limited depth along their meeting edges arranged to receive and crease a fold of an upper, and means for forcing the work into the groove formed by said recesses. 25
30. 13. In an upper creasing machine, a presser member divided into grippers provided with co-operating recesses along the meeting edges of said grippers, a rib for forcing the work into the groove formed by the recesses in the adjacent edges of the grippers, means urging said grippers together, and means for removing the rib constructed and arranged to allow the work to remain in the groove formed in the grippers, 35 whereby said grippers will be allowed to approach closely together and firmly impress an upstanding crease in the surface of the work. 40
45. 14. In a machine for forming a crease in a finished shoe, creasing members arranged to be disposed outside the shoe and having rabbeted edges shaped to conform to the curvature of the portion of the work to be creased, and means for moving said members apart to allow the introduction therebetween of a portion of the work to be creased. 50
55. 15. In a machine for forming a crease in a finished shoe, creasing members arranged to be disposed outside the shoe and having rabbets along their co-operating edges shaped to conform to the curvature of the portion of the work to be creased, means including a lever for separating said members to allow the introduction therebetween of a portion of the work to be creased, and resilient means urging said creasing members together. 60
65. 16. In a machine for forming a crease in a finished shoe, creasing members arranged outside a shoe and shaped to conform to the curvature of the portion of the work to be creased, means for separating said members to allow the introduction therebetween of the work to be creased, and a similarly shaped ribbed member arranged to be inserted within the shoe and to co-operate with said creasing members in introducing the work within the creasing members. 70
17. In a machine for forming a crease longitudinally of the toe of a finished shoe, a grooved creasing member shaped to conform to the curvature of the toe of the shoe, a similarly shaped ribbed member, means for bringing said members together, and means for causing the grooved member to press the work against the sides of the rib. 75
18. In a machine for forming a crease longitudinally of the toe of a finished shoe, a two-piece grooved creasing member shaped to conform to the curvature of the toe of the shoe, a similarly shaped ribbed member, and means for urging the two parts of said creasing member toward each other against separated portions of an upstanding crease in the work. 80
19. In an upper creasing machine, a presser member comprising grippers provided with co-operating recesses forming a groove along the meeting edges of said grippers, a headed stud passing through said grippers, a compression spring surrounding said stud arranged to force the grippers together, a button passing through one gripper and bearing against the inner face of the other gripper, and a hand lever pivoted to the former gripper constructed and arranged to depress said button in order to separate the grippers to enlarge the groove. 85
100. 20. In an upper creasing machine, a supporting frame provided with a tree adapted to support a finished shoe, a plunger movable in said frame, a creasing member supported on said plunger, said creasing member being provided with a movable part, means for moving said latter part away from the other part of the creasing member to allow the introduction of a piece of the work therebetween, and means for urging the parts of said creasing member toward one another. 105
110. 21. In an upper creasing machine, a supporting frame, a tree on said frame adapted for insertion in a finished shoe, said tree being provided with a blade shaped to form a rib on the tree conforming to the curvature of the inside of the shoe, a plunger movable in said frame, grippers on said plunger one of which is pivotally mounted with respect thereto, means for separating said grippers, means for urging the grippers together, and means for moving said plunger to bring the grippers into co-operative relation with the rib on the supporting tree. 115
120. In testimony whereof I have signed my name to this specification.

HARRIE A. BALLARD.
